BENJAMIN HARNISH AND ROBERT J. KING, OF LANCASTER, PENNSYLVANIA.

Letters Patent No. 87,667, dated March 9, 1869.

IMPROVEMENT IN PORTABLE MILLS.

The Schedule referred to in these Letters Patent and making part of the same.

To all whom it may concern:

Be it known that we, BENJAMIN HARNISH, (miller,) and ROBERT J. KING, of Lancaster, in the county of Lancaster, and State of Pennsylvania, have invented a new and useful Improvement on Portable Mills; and we do hereby declare that the following is a full, clear, and exact description of the construction and operation of the same, reference being had to the accompanying drawings, making a part of this specification, in which—

Figure 1 is a perspective view of a mill with our improvements in place.

Figure 2 shows the pulley D of the cracker-spindle, and pulley B of the burrs, with the belt F driving both.

Figure 3 shows the sieve-spout V and separating-spout W, in relation to the eye of the stone and outer casing and burrs.

Figure 4 shows the cracker C, with a cap, X, having an opening to receive ears of corn.

G, a bill-hook knife, adjustable on the spindle T, with a set-screw, S.

R is a gauge-ring, adjustable by washers interposed. O, feed-spout.

P, slide-plate over the knife.

The nature of our invention consists in using a cracker separate and apart from the burrs, so combined, however, as to be driven by the action of the same strap or belt which drives the burr, without additional gear, other than an ordinary tightening-pulley; also, in the diminished eye of the burr, so as to greatly increase the grinding-surface, and in sifting the finer particles, as they come from the cracker, so that the coarser particles that require grinding only enter the eye of the burr, thereby greatly relieving the tendency to clog, and secure a greater yield at a much less expense of power.

To enable others skilled in the art to make and use our improvement, a brief description will suffice.

Fig. 1 shows the frame-work and parts in perspective. A is a sheet-iron or wooden case, surrounding the burrs in the usual manner.

We claim no special novelty in the burrs or driving-pulley, B, attached to the spindle. We, however, do not hollow out the eye of the burrs in the usual manner, but leave it nearly flat, thereby greatly increasing the grinding-surface.

The pulley B, for the burrs, is one foot in diameter. The pulley D, that drives the spindle or grinding-cone of the cracker, is, say, three feet in diameter, and so

placed as to perform the office of a belt-tightener, as shown.

Thus, we do away with all the friction or wear and expense of cog-gearing, and greatly simplify the machinery, and reduce the power required to drive the mill; and, as we confidently believe, from the results; after a full and satisfactory trial, greatly increasing the amount ground per hour over other mills running burrs of like size.

The cracking-mill C is of the ordinary pattern, only that we can use plain or reversible segments, locking each other, and secured by a slot and flange-lug, so that a worn-out or injured segment or segments can be readily replaced.

The manner of grooving may be as novel as we find it useful.

Fig. 4 shows the conic grinding-nut, or core.

We also have a sieve in the spout V, that feeds the cracked grain to the eye E of the mill, or burr, with an additional spout, W, under it, inclined from both sides or ends of the upper spout, to convey the finely-ground or sifted portions inside of the case, or space that surrounds the stone, whence it finds its way out through the discharge-spout M, with the ground materials from the burrs, or grinding-surface.

We find that at least one-tenth is sufficiently fine, as it comes from the cracker, and by thus separating it, and preventing it from entering the eye of the stone, we increase the yield, and again lessen the amount of power.

We are aware of the numerous devices patented for grinding-mills, and therefore confine our claims to the mode of driving the cracker and burrs by the same strap, and the trough and sieve-arrangement, leading from the cracker to the burrs, and outer space between the burr and case.

What we claim as our invention, and desire to secure by Letters Patent, is—

The combination of the cracking-mill C and grinding-burrs, as shown, within their case A, the two mills connected by the compound chute and separator W V, and driven together by means of the belt F and pulleys B D, all arranged and operated as and for the purpose herein set forth.

B. HARNISH.
ROBT. KING.
